Office action/Restriction requirement dated Dec. 15, 2021 in U.S. Appl. No. 29/764,528.

Primary Examiner — Katie Jane Stofko

(74) *Attorney, Agent, or Firm* — Michael A. Olshavsky

(57) **CLAIM**

The ornamental design of a pet treat, as shown and described.

DESCRIPTION

FIG. 1 is a front perspective view of a first embodiment of a pet treat;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a front perspective view of a second embodiment of a pet treat;

FIG. 9 is a rear perspective view thereof;

FIG. 10 is a front elevation view thereof;

FIG. 11 is a rear elevation view thereof;

FIG. 12 is a top plan view thereof;

FIG. 13 is a bottom plan view thereof;

FIG. 14 is a right side elevation view thereof; and,

FIG. 15 is a left side elevation view thereof.

The broken lines in the figures are for the purpose of illustrating unclaimed portions of the pet treat and form no part of the claimed design.

1 Claim, 7 Drawing Sheets
